UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

PLANOGRAPHIC-PRINTING MACHINE.

1,272,032.

Specification of Letters Patent.

Patented July 9, 1918.

Application filed December 19, 1916. Serial No. 137,762.

To all whom it may concern:

Be it known that I, SAMUEL G. Goss, a citizen of the United States, and a resident of Glencoe, in the county of Cook and State of Illinois, have invented certain new and useful Improvements in Planographic-Printing Machines, of which the following is a specification, reference being had to the accompanying drawings.

10 My invention relates to planographic printing machines of the general type shown in the application of Ernest James Smith, Serial No. 111,603, filed July 27, 1916, and it has for its principal object the provision of a new and improved form and arrangement of driving means and of means for controlling the water and inking mechanisms and for moving the transfer cylinders out of contact with the form cylinders. It is 15 one of the objects of the invention to provide an improved arrangement of parts by reason of which the form cylinders and the inking mechanism may be operated without a corresponding forward movement of the web, whereby at the start of the operation of the machine the inking mechanism may be operated by itself for obtaining a properly inked condition prior to the start of the printing operation. It is another object of 20 my invention to provide improved means for insuring that the transfer cylinders shall be moved out of contact with the form cylinders whenever the press is brought to rest at the close of a printing operation, or is brought to its slow-speed operation for any reason. It is another object of the invention to provide improved mechanism whereby the press may be operated at slow speed, with the folder and other web-forwarding parts thrown out of operation, serving thus to keep the designs upon the form cylinders in proper condition for a subsequent continuation of the run of the press. It is another object of my invention 25 to provide automatically-acting means for throwing the folder and other web-forwarding mechanisms out of operation when the variable speed driving is changed from the high-speed to the low-speed operation. It is another object of my invention to improve planographic printing machines of this general type in sundry details as pointed out hereinafter. The preferred means by which I have accomplished my several

objects are illustrated in the drawings and are hereinafter specifically described. That which I believe to be new and desire to cover by this application is set forth in the claims.

In the drawings:

Figure 1 is a side view of a press embodying the preferred form of my improvements, looking toward the ends of the cylinders of the press;

Fig. 2 is a plan view of the motor and the connecting driving mechanism by which the press is given either a high speed or a low speed operation; and

Fig. 3 is a view showing the form of pawl and ratchet mechanism for connecting two of the gears of the driving mechanism to their respective shafts.

Referring to the several figures of the drawings, in which corresponding parts are indicated by the same reference characters,

75 10 indicates the framework of the press having form cylinders 11-12 revolvably mounted upon shafts 13-14, respectively, journaled in said frame, said form cylinders being adapted in the construction 80 shown to support planographic forms of any approved type. Movable mounted adjacent to the form cylinders 11-12 are two transfer cylinders 15-16 journaled by means of shafts 17-18, respectively, in bearing-blocks 19-20 which are movable diagonally downward and outward so as to carry the cylinders 15-16 out of contact with the form cylinders and out of operative engagement with each other. In the construction 90 shown, each of the blocks 19-20 is supported by a pair of toggle arms 21 connected together by an adjustable link 22 whereby the cylinders 15-16 are adapted to be moved in unison, as hereinafter described. 95

The form cylinders 11-12 are adapted to be driven from the cylinders 15-16 by means of intermeshing gears, the cylinder 15 being in turn driven from the cylinder 16. The construction is such that when the 100 cylinders 15-16 are moved downward and away from each other the teeth of the driving gears are continued in meshing engagement whereby the driving relations continue even after the operative engagement of the 105 cylinders has been discontinued. The cylinder 16 is driven in clockwise direction in Fig. 1 by means of a gear 23 which in turn

is driven by means of a gear 24 meshing with the high-speed gear 25 of the driving mechanism.

Referring now particularly to Figs. 2 and 3 for a brief description of the driving mechanism, 26 indicates a motor of any suitable type having a gear 27 mounted upon its drive shaft 28. A large gear 29 meshing with the gear 27 is revolvably mounted upon 10 a laterally-extending shaft 30, a clutch mechanism 31 being adapted for connecting said gear 29 with the shaft 30 as may be desired, the connection being effected through a stroke of a lever 32 connected with the 15 clutch mechanism and actuated as hereinbefore described. The gear 25 above referred to is revolvably mounted upon the shaft 30, being connected by means of pawls 33 and a ratchet 34 with the said shaft 30 whereby 20 upon the rotation of the shaft 30 in counterclockwise direction in Fig. 3 the gear 25 is driven thereby, serving to drive the cylinder 16 in clockwise direction in Fig. 1. The proportions of the train of driving mechanism 25 from the motor 26 to the cylinder 16 as above described are such as to drive the cylinder 16 at the desired normal high-speed rotation.

The shaft 30 is connected by means of 30 bevel gears 35-36 with a longitudinally-extending shaft 37 which is connected by means of gears 38, 39 and 40 with a folding mechanism 41 of any suitable type, whereby such folding mechanism is adapted to be 35 driven at the desired speed of rotation from the shaft 30. A bevel gear 42 is connected with the driving gear 40 so as to rotate therewith, said bevel gear 42 being in mesh with a bevel gear 43 mounted upon a vertically-extending shaft 44. The shaft 44 is connected by means of bevel gears 45-46 with a longitudinally-extending shaft 47 which is connected by means of bevel gears 48-49 with a roller 50 about which the web 51 40 passes in its movement from the transfer cylinders 15-16 to the folder 41. The shaft 44 is also connected by means of bevel gears 52-53 with a longitudinally-extending shaft 54 which is connected by means of bevel 45 gears 55-56 with a web-forwarding roller 57.

Means is provided for driving the gear 25 from the gear 29 independently of the shaft 30 and at a comparatively much lower rate 55 of rotation, the arrangement being such that the cylinders 15-16 may be driven at the slower speed while the folder 41 and the web-forwarding rollers 50 and 57 are permitted to remain silent. This means 60 comprises a pinion 58 revolvably mounted upon the shaft 30 so as to rotate with the gear 29, the pinion 58 being in mesh with a gear 59 revolvably mounted upon a shaft 60. The gear 59 is adapted to be operatively connected with the shaft 60 by means of a

clutch mechanism 61 which is adapted to be thrown into operation by a proper stroke of a lever 62 which is connected by means of a link 63 with an operating lever 64 (see Fig. 1). The shaft 60 is provided with a gear 65 revolvably mounted thereon and connected thereto by means of pawls 66 carried by the gear adapted to engage a ratchet 67 fixedly mounted upon the shaft. As is best shown in Fig. 3, the arrangement of the pawl and ratchet mechanism is such that upon the rotation of the shaft 60 in clockwise direction in Fig. 3 the gear 65 will be driven in the same direction by the pawl 66 unless such gear is being driven more rapidly in the same direction by the gear 25 with which it meshes.

As will be readily understood from an examination of Figs. 2 and 3, when the gear 27 is driven in the direction indicated by the arrow thereon, with the clutch 31 in operation for connecting the gear 29 to the shaft 30, the gear 25 will be driven at the normal high-speed in counterclockwise direction in Fig. 3, serving to drive the gear 65 at the same speed in clockwise direction in said figure. At the same time the shaft 60 will be driven in clockwise direction in Fig. 3 at the slow speed rate of rotation through the pinion 58 and the gear 59. It will be understood that the clutch 61 might be thrown out of operation for disconnecting the gear 59 from the shaft 60, but ordinarily this would not be done, inasmuch as it is unnecessary for the proper operation of the device. 100 When it is desired to silence the web-forwarding means and the folder, and to drive the cylinders 15-16 at their slow-speed rotation, the clutch 31 is thrown out of operation, whereupon the shafts 30 and 37 are 105 silenced and the driving of the gear 25 continues through the medium of the shaft 60 and the gear 65, in the same direction as formerly but at the slower speed.

Means is provided for shifting from the high-speed to the low-speed operation, serving at the same time to move the cylinders 15-16 out of operative position. This means comprises a lever 68 pivotally mounted upon the framework 10 and provided 110 with a toothed sector 69 which meshes with a gear 70 fixedly mounted upon a rotary cam member 71. The cam member 71 is provided with a cam slot 72 which operates in connection with a stud or roller 73 mounted 115 upon an arm 74 fixedly mounted upon the shaft 75 upon which one of the lower toggle-arms 21 is fixedly mounted. The construction is such that upon the initial portion of a stroke of the lever 68 toward the left in Fig. 1, the arm 74 is moved toward the right in said figure, buckling both sets of toggle-arms 21 toward the right and serving 120 thus to move the transfer cylinders 15-16 slightly out of operative position. 130

The same rotation of the shaft 75 serves to swing a toothed sector 76 toward the left in said Fig. 1, serving to rotate an intermeshing toothed sector 77 in clockwise direction in Fig. 2. The sector 77 is connected by means of an arm 78 and a link 79 with the lever 32, whereby, upon the movement of the sector 77 in clockwise direction in Fig. 2, the lever 32 is moved in counterclockwise direction in said figure serving to throw the clutch 31 out of operation. This expedient has the result, as above explained, of changing the drive from the high speed to the low speed.

Inking mechanism is provided for the form rollers 11-12, comprising inking cylinders 80-81 revolvably mounted upon the framework 10 by means of shafts 82-83, respectively. The ink is carried from the cylinders 80-81 to the form cylinders 11-12 by means of suitable inking mechanisms carried by frames 84 journaled upon the shafts 82-83, the construction and arrangement being such that when the frames 84 are swung outward away from each other the form rollers 85 carried by said frames are moved out of contact with the form cylinders. Ink is fed to the inking cylinders 80-81 by means of any suitable train of mechanisms comprising reciprocating rollers 86 which are actuated by means of cams 87 of any suitable type and driven from any suitable source of power. Ink is supplied to the reciprocating rollers 86 from fountain rollers 88 which are driven intermittently by means comprising links 89 connected with the cams 87 and reciprocated thereby. The links 89 are connected at their upper ends with arms 90 which in turn are connected with arms 91 which are provided with pawls 92 engaging ratchet wheels 93 which are adapted to rotate with the fountain rollers 88. Shroud-plates 94 are swingingly mounted adjacent to the pawls 92, adapted to be moved by means of arms 95 into position to throw the pawls 92 out of operation, whereby upon the continued rotation of the cams 87 the form rollers 88 are caused to remain silent. The arms 95 are adapted to be swung, for moving the shroud-plates 94, by means of links 96 connected at their lower ends to bell-crank levers 97 which are connected by means of longitudinally-extending links 98-99 with the lower end of an arm 100 which is pivotally mounted upon the framework 10. The arm 100 is provided with a stud or roller 101 which works in a cam groove 102 formed in the cam member 71, the arrangement being such that, upon the next-succeeding portion of the rotation of the cam member following the initial portion by which the cylinders 11-12 are thrown out of operative position, the arm 100 is swung toward the right in Fig. 1, serving to move the links 98-99 toward the right for carrying the links 96 and the arms 95 downward, serving to throw the pawls 92 out of operation. By this expedient, the supply of fresh ink to the inking cylinders 80-81 and from such cylinders to the form cylinders 11-12 is cut off.

Means is provided for swinging the frames 84 outward for carrying the form rollers 85 out of contact with the form cylinders 11-12, comprising gears 103 fixedly mounted upon rock-shafts 104 which are connected with said frames by means of links 105 and eccentrics 106. The arrangement is such that upon the rotation of the shafts 104 in either direction the frames 84 are moved outward away from each other. The shafts 104 and the gears 103 are adapted to be rotated in unison by means of toothed sectors 107 which are revolvably mounted upon the shafts 13-14 of the form cylinders, being connected together by a link 108. One of the sectors 107 is provided with an adjustable arm 107' which is connected by means of a link 109 with a bell-crank lever 110 one arm of which is provided with a stud or roller 111 working in a cam slot 112 in the cam member 71. The arrangement is such that, upon the portion of the rotation of the cam member 71 following that by which the supply of ink is cut off from the inking cylinders 80-81, the lever 110 is moved in counterclock-wise direction in Fig. 1 serving to swing the sectors 107 in unison toward the left in said figure, serving to move the form rollers 85 out of operative contact with the form cylinders 11-12.

Water mechanism is provided for each of the form cylinders 11-12 comprising frames 113 pivotally mounted upon the framework 10, said frames being provided with any suitable form of mechanism by which moisture may be applied to the form cylinders. In the construction shown, the water mechanisms comprise rollers 114 which are adapted to be moved out of contact with the form cylinders 11-12 upon an appropriate swinging of the frames 113, as will be readily understood. The frames 113 are provided with arms 115-116 fixedly connected thereto, said arms being connected together by a link 117 which in turn is connected by means of a link 118 with a lever 119. The lever 119 is provided with a stud or roller 120 which works in a cam groove 121 formed in the cam member 71, the arrangement being such that, upon the portion of the rotation of the cam member 71 following that by which the form rollers 85 are thrown out of operative position relative to the cylinders 11-12, the water rollers 114 are moved out of operative contact with the said cylinders 11-12.

As will be appreciated from the above description, when the lever 68 is given its initial movement for changing from the high-speed to the low-speed operation, the folder 130

and web-forwarding means are thrown out of operation and the transfer cylinders 15-16 are thrown out of operative position relative to each other and relative to the 5 form cylinders 11-12. With the parts in this position, the form cylinders 11-12 may be operated at slow speed with both the inking mechanism and the water mechanism in operation, the designs upon the form 10 cylinders 11-12 being thus kept in proper condition. If it is desired to keep the form cylinders 11-12 in rotation at the slow-speed with the form rollers 85 in contact therewith, but with the supply of fresh ink 15 cut off from the form rollers 85, this may be accomplished by a further stroke of the lever 68. A still further stroke of the lever serves to throw the form rollers 85 out of contact 20 with the form cylinders, and the final portion of the stroke of the lever 68 serves to throw the water mechanisms out of operative position. The press can then be stopped either by stopping the rotation of the motor 25 26 or by throwing the clutch 61 out of operation through the medium of the lever 64. When the press is being started into operation with a fresh design upon the form cylinders, it is often desirable that the form cylinders be properly inked before the movement of the web between the transfer cylinders is started. This result may be brought about by a movement of the lever 68 in the direction for starting the press, restricting the movement to approximately three-quarters 30 of its complete stroke whereby the form cylinders will be rotated at slow-speed with the water mechanisms and the inking mechanisms in full operation, but with the web silent. When the cylinders 11-12 have attained a properly inked condition, the lever 35 68 can be given the final portion of its stroke for bringing the transfer cylinders into operative position and for otherwise bringing the press into condition for effective operation. 40

That which I claim as my invention, and desire to secure by Letters Patent, is,—

1. In a printing machine, the combination of a form-cylinder, a folder, variable speed mechanism for driving said form-cylinder and said folder at normal high speed in operative relation to each other, and means serving to throw said folder out of operation when the driving mechanism is shifted from its high speed to its low speed.
2. In a printing machine, the combination of a form-cylinder, a folder, driving mechanism comprising a high speed shaft and a low speed shaft, means operatively connecting said high speed shaft with said form-cylinder and said folder for driving them at normal speed in operative relation to each other, and means operatively connecting said low speed shaft with said form-

cylinder adapted to permit said folder to 65 remain silent upon the low speed driving.

3. In a printing machine, the combination of a form-cylinder, a folder, a driving member operatively connected with said folder for driving it, a second driving member 70 operatively connected with said form-cylinder for driving it, connections between said first-named driving member and said second member adapted to cause said second member to rotate upon the rotation of said 75 first-named member in its operative direction but adapted to permit said second member to rotate in the same direction independently of the first-named member, and means for driving said second member independently of said first-named member. 80

4. In a printing machine, the combination of a form-cylinder, a folder, a high speed driving shaft operatively connected with said folder for driving it at normal 85 high speed, a gear operatively connected with said form-cylinder for driving it, connections between said shaft and said gear adapted to cause said gear to rotate upon the rotation of said shaft for driving said 90 folder but adapted to permit the gear to rotate in the same direction independently of the shaft, and means for driving said gear at slow speed independently of said shaft. 95

5. In a printing machine, the combination of a form-cylinder, a folder, a high speed driving shaft operatively connected with said folder for driving it at normal 100 high speed, a gear operatively connected with said form-cylinder for driving it, pawl-and-ratchet connections between said shaft and said gear adapted to cause said gear to rotate upon the rotation of the shaft for driving said folder but adapted to permit the gear to rotate in the same direction independently of the shaft, and means for driving said gear at slow speed independently of said shaft. 105

6. In a printing machine, the combination of a form-cylinder, a folder, a high speed driving shaft operatively connected with said folder for driving it at normal 110 high speed, a gear operatively connected with said form-cylinder for driving it, connections between said shaft and said gear adapted to cause said gear to rotate upon the rotation of the shaft for driving said folder but adapted to permit the gear to rotate independently of the shaft, and means 115 for driving said gear at slow speed adapted when the shaft is silenced to drive said gear at slow speed. 120

7. In a printing machine, the combination of a form-cylinder, a folder, a high speed driving shaft operatively connected 125 with said folder for driving it at normal high speed, a gear operatively connected with said form-cylinder for driving it, con-

- nections between said shaft and said gear adapted to cause said gear to rotate upon the rotation of the shaft for driving said folder but adapted to permit the gear to 5 rotate independently of the shaft, and constantly-driven means adapted to permit said gear to rotate at high speed but adapted when the high speed driving means is disconnected therefrom to drive the gear at 10 low speed.
8. In a printing machine, the combination of a form-cylinder, a folder, a high speed driving shaft operatively connected with said folder for driving it at normal 15 high speed, a gear operatively connected with said form-cylinder for driving it, pawl-and-ratchet connections between said shaft and said gear adapted to cause said gear to rotate upon the rotation of the 20 shaft for driving said folder but adapted to permit the gear to rotate in the same direction independently of the shaft, and means comprising pawl-and-ratchet mechanism for driving said gear at slow speed but 25 adapted to permit the high speed rotation of the gear in the same direction.
9. In a planographic printing machine, the combination of a form-cylinder, a transfer cylinder movably mounted adjacent to said 30 form-cylinder and adapted to coöperate therewith, variable speed mechanism for driving said form-cylinder at either high speed or low speed, and means for throwing said high speed driving mechanism out of 35 operation and for simultaneously moving said transfer cylinder out of operative contact with said form-cylinder.
10. In a planographic printing machine, the combination of a form-cylinder, a transfer cylinder movably mounted adjacent to said form-cylinder and adapted to coöperate therewith, means for forwarding a web through said machine, variable speed mechanism for driving said form-cylinder and 40 said web-forwarding means at high speed, and means for throwing said high speed driving mechanism out of operation and for simultaneously moving said transfer cylinder out of operative contact with said 45 form-cylinder, serving at the same time to throw said web-forwarding means out of operation.
11. In a planographic printing machine, the combination of a form-cylinder, a transfer cylinder movably mounted adjacent to said form-cylinder and adapted to coöperate therewith, a folder, variable speed mechanism for driving said form-cylinder and 50 said folder at high speed, and means for throwing said high speed driving mechanism out of operation and for simultaneously moving said transfer cylinder out of operative position relative to said form-cylinder, serving at the same time to throw 55 said folder out of operation.
12. In a planographic printing machine, the combination of a form-cylinder, a transfer cylinder movably mounted adjacent to said form-cylinder and adapted to coöperate therewith, inking mechanism for applying ink to said form-cylinder, variable speed mechanism for driving said form-cylinder at either high speed or low speed, and a movable member by a partial operative stroke of which the high speed driving 70 mechanism is thrown out of operation and by the next following portion of the stroke of which the supply of fresh ink is cut off from said inking mechanism.
13. In a planographic printing machine, the combination of a form-cylinder, a transfer cylinder movably mounted adjacent to said form-cylinder and adapted to coöperate therewith, inking mechanism for applying ink to said form-cylinder, variable speed 75 mechanism for driving said form-cylinder at either high speed or low speed, a movable member by a partial operative stroke of which the high speed driving mechanism is thrown out of operation, means actuated by the next following portion of the stroke of said movable member for cutting off the supply of fresh ink from said inking mechanism, and means actuated by a succeeding portion of the stroke of said movable member for throwing said inking mechanism out of operative position relative to said form-cylinder.
14. In a planographic printing machine, the combination of a form-cylinder, a transfer cylinder movably mounted adjacent to said form-cylinder and adapted to coöperate therewith, inking mechanism for applying ink to said form-cylinder, water mechanism for applying water to said 100 form-cylinder in advance of the application of ink thereto, variable speed mechanism for driving said form-cylinder at either high speed or low speed, a movable member by a partial operative stroke of which the high speed driving mechanism is thrown out of operation, means actuated by the next following portion of the stroke of said movable member for cutting off the supply of fresh ink from said inking mechanism, means actuated by the succeeding portion of the stroke of said movable member for throwing said inking mechanism out of operative position relative to said form-cylinder, and means actuated by the 105 succeeding portion of the stroke of said movable member for throwing said water mechanism out of operation.
15. In a planographic printing machine, the combination of a form-cylinder, a transfer cylinder movably mounted adjacent to said form-cylinder and adapted to coöperate therewith, inking mechanism for applying ink to said form-cylinder, water mechanism for applying water to said form- 110

- cylinder in advance of the application of ink thereto, variable speed mechanism for driving said form-cylinder at either high speed or low speed, a movable member by a 5 partial operative stroke of which the high speed driving mechanism is thrown out of operation, means actuated by the next following portion of the stroke of said movable member for cutting off the supply of fresh 10 ink from said inking mechanism, means actuated by the succeeding portion of the stroke of said movable member for throwing said inking mechanism out of operative position relative to said form-cylinder, and 15 means actuated by the succeeding portion of the stroke of said movable member for throwing said water mechanism out of operative position relative to said form-cylinder.
16. In a planographic printing machine, 20 the combination of a form-cylinder, a transfer cylinder movably mounted adjacent to said form-cylinder and adapted to coöperate therewith, inking mechanism for applying ink to said form-cylinder, water mechanism 25 for applying water to said form-cylinder in advance of the application of ink thereto, variable speed mechanism for driving said form-cylinder at either high speed or low speed, a lever, a cam actuated 30 by a partial stroke of said lever for throwing said high speed driving mechanism out of operation, a cam actuated by the next following portion of the stroke of said lever for cutting off the supply of fresh ink from 35 said inking mechanism, a cam actuated by the next following portion of the stroke of said lever for throwing said inking mechanism out of operative position relative to said form-cylinder, and a cam actuated by 40 the next following portion of the stroke of said lever for throwing said water mechanism out of operative position relative to said form-cylinder.
17. In a planographic printing machine, 45 the combination of a form-cylinder, a transfer cylinder movably mounted adjacent to said form-cylinder and adapted to coöperate therewith, inking mechanism for applying ink to said form-cylinder, water mechanism 50 for applying water to said form-cylinder in advance of the application of ink thereto, variable speed mechanism for driving said form-cylinder at either high speed or low speed, a movable member by a partial operative 55 stroke of which the high speed driving mechanism is thrown out of operation and said transfer cylinder is moved out of operative position relative to said form-cylinder, means actuated by the next following portion 60 of the stroke of said movable member for cutting off the supply of fresh ink from said inking mechanism, means actuated by the succeeding portion of the stroke of said 65 movable member for throwing said inking mechanism out of operative position relative to said form-cylinder, and means actuated by the succeeding portion of the stroke of said movable member for throwing said water mechanism out of operation.
18. In a planographic printing machine, 70 the combination of a form-cylinder, a transfer cylinder movably mounted adjacent to said form-cylinder and adapted to coöperate therewith, inking mechanism for applying ink to said form-cylinder, water mechanism 75 for applying water to said form-cylinder in advance of the application of ink thereto, means for forwarding a web through said machine, variable speed mechanism for driving said form-cylinder at either high speed or 80 low speed, a movable member by a partial operative stroke of which the high speed driving mechanism is thrown out of operation, means actuated by the same portion of the stroke of said movable member for throwing said transfer cylinder out of operative position relative to said form-cylinder, means actuated by the same portion of the stroke of said movable member for throwing said web-forwarding means out of operation, means actuated by the next following portion of the stroke of said movable member for cutting off the supply of fresh ink from 85 said inking mechanism, means actuated by the succeeding portion of the stroke of said movable member for throwing said inking mechanism out of operative position relative to said form-cylinder, and means actuated by the succeeding portion of the stroke of said movable member for throwing said 90 water mechanism out of operation.
19. In a planographic printing machine, 95 the combination of a form-cylinder, a transfer cylinder movably mounted adjacent to said form-cylinder and adapted to coöperate therewith, inking mechanism for applying ink to said form-cylinder, water mechanism 100 for applying water to said form-cylinder in advance of the application of ink thereto, variable speed mechanism for driving said form-cylinder at either high speed or low speed, cam means adapted upon a partial rotation to throw said high speed mechanism out of operation, means actuated by the next-succeeding portion of the rotation of said cam means for cutting off the supply of fresh ink from said form-cylinder, means actuated by the next-succeeding portion of the rotation of said cam means for throwing said inking mechanism out of operative position relative to said form-cylinder, and means operated by the next-succeeding portion of the rotation of said cam means for throwing said water mechanism out of operative position relative to said form-cylinder. 120
